DESIGN FOR A GLOVE

John E. Fuchs, New York, N. Y.

Application January 8, 1937, Serial No. 66,961

Term of patent 3½ years

To all whom it may concern:

Be it known that I, John E. Fuchs, a citizen of the United States of America, residing in Manhattan, county of New York, and State of New York, have invented a new, original, and ornamental Design for a Glove, of which the following is a specification, reference being had to the accompanying drawing, forming part thereof, wherein,

I claim:

The ornamental design for a glove, substantially as shown.

JOHN E. FUCHS.
